GUN CARRIAGE

Charles K. Woodman, Beverly, Mass., assignor to
 United Shoe Machinery Corporation, Flemington, N. J., a corporation of New Jersey

Application April 30, 1945, Serial No. 591,133

4 Claims. (Cl. 89—40)

1

This invention relates to carriages upon which such an article as a gun may be transferred from one point to another, it being especially adapted for raising the gun-mount from a surface upon which it rests, as the deck of a vessel, supporting it upon wheels for its travel, lowering it again to the supporting surface of a firing platform, and there securing it for firing.

It is an object of the invention to provide for the attachment of the carriage to the supporting surface in its lowered relation by means which will effectively resist the shock of gun-discharge, and the operation of which will not be interfered with by the entrance of dirt. In the carriage-body, a positioning member, preferably in the form of a sleeve, is rotatable, and by this member a spindle is rotatable, as by a splined connection between the two. By the positioning member, the spindle may be turned so that a head upon it is adapted to enter a deck-socket, after which it may be further turned for engagement with said socket. In the latter position, the rotation of a clamping member may be caused to move the spindle longitudinally, as by threaded engagement between the spindle and the clamping member, to effect final clamping engagement. The threaded elements are so located in the carriage that dirt and moisture are not liable to enter between them, while the socket in the supporting surface and the co-operating spindle-head may be of such a character that the presence of dirt will not affect them. An actuating member arranged for manual operation is joined to the clamping member by ratchet mechanism, so its action may be transmitted to said clamping member in short, effective strokes, and by employing a reversible ratchet the actuating member may be caused both to produce clamping engagement of the spindle-head with the socket and to free it therefrom.

In the accompanying drawings, one of several possible embodiments of the invention is illustrated,

Fig. 1 showing my improved carriage in side elevation and in firing position;

Fig. 2 is a similar partial view with the elements in towing position, the standard of the gun-mount being removed;

Fig. 3, a top plan view, the upper portion of the gun-standard being sectioned;

Fig. 4, a rear elevation of the carriage, with parts removed;

Fig. 5, an enlarged central vertical section, taken through the means for securing the carriage to its supporting surface;

2

Fig. 6, a horizontal sectional detail through the reversible ratchet of the securing means; and
 Fig. 7, a top plan view of the deck-socket which the securing means engages.

At 10 appears the standard of a mount for a gun, the legs of which standard rise from a base-ring 12. Attached to the lower face of the base is a spider 14, screws 16 passing through the base-ring and being threaded into each of the five arms of the spider near their outer extremities and into lugs 18 cast upon the bottom of the spider-arms. The lugs are at substantially equal distances from the center of the spider, and supply a uniform five-point bearing when the spider supports the gun upon the deck. The arms 20, 20 of the spider diverge outwardly to the rear at equal angles to the center-line of the carriage, and their screws secure to the top of the base-ring 12 a transverse bar 22 of a rear wheel-assembly A. The front spider-arms 24, 24 are connected at 25, and upon this connecting portion is formed an extension 26 along the center line of the carriage beyond the base-ring, while to said ring by the screws of the spider-arms 24, 24 a forwardly and upwardly extending bracket 28 is secured. The base-ring 12, the bar 22 and the bracket 28, because of their fixed attachment to the spider 14, may be considered as portions of the carriage-body. In the spider-extension 26 and in the bracket 28 are vertically aligned openings to receive the pintle 29 of a forward truck or limber B.

Mounted to turn in horizontal alinement in the bar 22, and spaced from each other at their inner ends, are spindles 30, 30. Fixed to the outer extremity of each spindle is a short arm 32, the two arms occupying the same angular position about the common axis of the spindles. Projecting outwardly from the end of each arm is an axle 34, upon which is rotatable a wheel 36. The adjacent inner ends of the spindles are fast in the opposite spaced side walls 38, 38 of an arm or handle 40, of much greater length than the arms 32, 32. The three arms furnish a compound bell-crank-lever which, in the position appearing in Fig. 2 of the drawings, places the arms 32, 32 vertically, their length being such that the lugs 18 are clear of the supporting surface, while the arm 40 extends outwardly from the standard. The rear of the carriage is thus ready for moving upon its wheels 36 from one position to another. To maintain the lever L with its wheels 36 in this towing relation, there is at the outer side of each handle-wall 38 a horizontal projection 42, lying in an arcuate slot 44 in one arm 46 of a double

latch *l* yoked together at *48*, and with the yoke pivoted to brackets *50* rising from the bar *22*. At the outer extremity of each slot is an offset portion *52*, each offset and the corresponding wall of the slot being urged toward the co-operating projection *42* by an expansion-spring *54* interposed between the bar *22* and an arm *56* projecting inwardly from the yoke of the latch. When the handle *40* is shifted outwardly to the position of Fig. 2 for towing, the projections ride along the lower walls of the latch-slots, and, when said projections have arrived at the ends of the slots, the offsets are carried up by the spring to the opposite sides of the projections. The bell-crank-lever *L* and the wheels which it carries are thus held against angular movement about the axis of the spindles *30*. In this latched position of the bell-crank-lever *L* for towing, the axles *34* lie directly beneath the fulcrum-spindles *30*, so the tendency of the lever to be displaced angularly by the weight of the carriage and gun is minimized. When it is desired to lower the carriage-body upon the wheels to the deck for firing the supported gun, the latch-arms are depressed by pressure on the latch-yoke *48*. This frees the projections *42* from the slot-offsets *52*, and the handle may be held to swing forwardly and the arms *32* rearwardly, the carriage-body descending so the lugs *18* rest upon the deck and the wheels *36* being entirely relieved of the weight of the carriage and gun. As appears in Fig. 1, the projections *42* are now at the inner ends of the slots *44*, the lever-arm *40* extends inwardly along the carriage and then rises close to the gun-standard *10*. This arm *40* is preferably formed of sheet metal, concave at its inner side to receive the adjacent portion of the standard. It may thus lie in such close proximity to said standard that it adds little to the horizontal dimension, and entirely avoids interference, as the gun is turned in train, with the cartridge-case-bag, which is hung between the gun-standard and the gun-cradle. This is true, even when the elevation is high and the bag is carried close to the standard. An outwardly curved U-shaped hand-hold *60*, at the top of arm *40*, furnishes means which may be more readily grasped to manipulate the lever *L*.

Fulcrumed at *62* on spaced side walls *64*, *64* of the truck *B* is a bell-crank-lever *L'*. This lever is of sheet metal, U-shaped in transverse section, with the arms of the U lying outside the truck-walls *64*. Extending below the fulcrum is a double short arm *66*, carrying a horizontal axle *68*, upon which between the sides of the arm a forward wheel *70* is rotatable. A substantially longer arm *72* of the bell-crank-lever *L'* extends in towing relation (Fig. 2) upwardly and forwardly, and has a hand-hold by which it may be grasped. The latch *74* for retaining the lever *L'* is similar to and acts in the same manner as the rear latch *l*. It is U-shaped, being pivoted at *76* outside the truck-walls *64* at the rear of the lever-arm *66*. Each arm of the U is provided with a slot *78*, having a retaining offset *80*, the ends of the axle *68* being movable along the slots and holding the lever *L'* in towing position when the offsets are drawn up to receive and retain the axle. This is effected by tension-springs *82* extending between the arms of the latch and the ends of the fulcrum *62*. When the lever *L'* is released from the latch by pressure upon a foot-plate *84*, the axle *68* travels forwardly along the slots *78*; the forward end of the carriage sinks to the deck or other supporting surface; and the lever-arm *72* is positioned similarly to the arm

40 of the lever *L* (Fig. 1). It first closely parallels the carriage, its transverse depression receiving the truck *64* and the bracket *28*. It then rises along the standard *10*, which is received by its concavity, so, as with the lever *L*, interference with the cartridge-case-bag is avoided.

In its lowered relation for firing the supported gun, the carriage is secured firmly by a clamping device *C* (Fig. 5), adapted to enter a socket *S* set in the deck *D* and to be drawn quickly into clamping relation. The socket has as its chief characteristics a cylindrical barrel *86* fitting a deck-opening, a lower flange *87* which holds the socket against upward displacement, an upper opening *88* which is elongated horizontally, as appears in Fig. 7, and a lower recess *89* which continues downwardly the opening *88* and then is extended horizontally at opposite sides, it terminating in vertical shoulders *90*, *90*, which furnish stop-surfaces. In the horizontal overhang *91* of the socket above each shoulder is a depression *92*. As best shown in Fig. 5, the spider *14* has at its center a cylindrical opening *93*, at the bottom of which is a shoulder *94* surrounding a reduced opening *96*. Within the spider-opening *93* is a positioning sleeve *98*, with its shouldered end *103* stepped upon the spider-shoulder *94*, and provided with an extension *102* lying within the spider-opening *96*. There is some clearance between the sleeve and the wall of the spider-opening, so said sleeve may be shifted laterally. Upon the upper extremity of the sleeve above the spider is a hand-wheel *104*. Splined at *106*, to move longitudinally through the sleeve-extension *102* while compelled to turn therewith, is the spindle or stem *108* of a socket-engaging member, at the lower end of which is a head *110*. This head is formed similarly to the socket-opening *88*, it being adapted to pass freely through this into the recess *89* and to be turned therein until arrested by contact with the shoulders *90*. The spindle *108* is threaded at *112* into a clamping member *114*, rotatable within the sleeve and resting upon an antifriction step-bearing *116* at the bottom of the sleeve. Rotation of the clamping member will cause the thread *112* to either raise the head when it is within the recess *89* for the clamping of the carriage, or lower said head to release it from its clamping engagement. To permit the member *114* to be rotated effectively, it has a cylindrical upward extension *118*, which is surrounded by an actuating sleeve *120* stepped at *122* on the body of the clamping member. The upper end of the extension is threaded to receive a cap *121* extending over the sleeve *120*. This retains the sleeve in place for its operation, yet permits it to be removed when desired. A packing-ring *124*, occupying a peripheral recess in the extension *118*, yieldably fills the space between the extension and the sleeve, and prevents the entrance of dirt and water to the bearing *116* and to the thread *112*. The sleeve *120* has a lateral extension *126* upon which is pivoted at *128* a hand-lever *130*, through which the sleeve may be rotated. This hand-lever may be turned down to a horizontal position limited by a stop-surface *132* on the extension *126* to give the maximum leverage, or may be raised, as appears in Fig. 5, and yieldably held in an inactive position by a spring-plunger *134* carried by the extension. To allow relatively short oscillations of the hand-lever to be transmitted to the actuating sleeve, there is carried in a bore in a casing *136* projecting from the sleeve a pawl *138*, urged inwardly by an expansion-spring *140* for engagement with

a peripheral series of teeth 142 about the extension 118 (Fig. 6). The pawl is shown as having a straight face 144 engaging the teeth to rotate the clamping member 114, and an opposite inclined face 146 which slips over the teeth. On the stem 148 of the pawl is a finger-piece 150, by which said pawl may be drawn out against the force of the spring 140, and a pin 152 set in the stem located in a slot 154 in the end of the casing 136 in either of the two positions 180° apart. Thus, the pawl-surface 144 may be effective to turn the member 114 in opposite directions.

When the gun-carriage is arranged as appears in Fig. 2 of the drawings, ready for towing from one point on the deck of a vessel to another, from which the gun is to be fired, the head 110 of the socket-engaging member lies within the opening 96 in the spider 14, wholly clear of the deck. This was effected by lifting the sleeve 98, which carries all the other elements of the clamping device C, through the hand-wheel 104 and retaining it in its inactive position by a latch 160 pivoted on the spider and forced beneath the lower edge of the sleeve by an expansion-spring 162. The bell-crank-levers L and L' are so swung outwardly, that the carriage has been lifted upon its wheels 36, 36 and 70, the ratio of the short arms of the two levers to the longer arms giving an advantage in leverage which renders the elevation easy. The offsets of the slots in the latches 1 and 14 have, respectively, engaged the projections 42 and the axle 68 to retain the levers in towing position. With the carriage thus raised, it is wheeled over a socket S in the deck D with the head 110 of the engaging member over the socket-opening 88. By successively depressing the rear and forward latches, the levers are released, and the lugs 18 allowed to sink to the deck. The concave lever-arms 40 and 72 now so embrace the gun-standard 10 at its opposite sides, that they project but little from it, and there is nothing to interfere with the movement of the gun in train. With the carriage lowered, the sleeve 98 is freed from the latch 160, so the device C descends, with the head 110 engaging the socket S. If necessary, by moving the sleeve 98 laterally in the spider and by turning the hand-wheel 104, the head is brought into registration with the socket-opening 88 and enters the recess 89. By turning the hand-wheel clockwise, the head is brought into contact with the socket-shoulders 90, 90. Now, by oscillating the hand-lever 130, with the pawl 138 set for effective engagement with the ratchet-teeth 142 in a clockwise direction, the clamping member 114 is turned to cause its thread to lift the spindle 108, forcing the laterally projecting portions of the head 110 up against the socket-overhang 91 and into the depressions 92. Thus, the socket-engaging member may be caused to clamp the gun-carriage to the deck as firmly as is desired. At the same time, because of the presence of the head in the socket-depressions 92, said head is locked against accidentally rotating away from the shoulders 91 to decrease the clamping force. When the carriage is to be again moved, the pawl 138 is reversed and the hand-lever 130 oscillated, this turning the clamping member 114 oppositely to that for securing the carriage and causing the head 110 to leave the socket-overhang 91, freeing it from the depressions 92. This release having been accomplished, the head is turned by the hand-wheel 104 back into registration with the opening 88, where it is stopped by engagement with shoulders 164 at the sides of the recess 89.

Then the device C may be lifted by the hand-wheel, until the latch 160 is forced by its spring beneath the sleeve 98, holding the head withdrawn into the spider. The lever-arms 40 and 72 are swung out from the standard 10, and the latches 1 and 14 secure the lever-arms 32 and 66, with the wheels 36 and 70 upon the deck and the carriage raised ready for towing.

Having described my invention, what I claim as new and desire to secure by Letters Patent of the United States is:

1. In a gun-carriage, a body adapted to rest upon a firing platform having a socket fixed therein, means for securing the body to the platform comprising a spindle, a positioning member connected to said spindle and mounted to rotate in said body, said spindle and socket having co-operating shoulders which are brought into locking relation by rotation of said spindle in the socket, and means for drawing said spindle toward said body whereby the latter is held against the platform.
2. In a gun-carriage, a body adapted to rest upon a firing platform having a socket fixed therein, means for securing the body to the platform comprising a spindle, a positioning member splined to said spindle and mounted to rotate in said body, said spindle having a shouldered head fitting within a complementary recess in the socket, a clamping member threaded on said spindle, and means for turning said clamping member to draw said spindle toward said body whereby the latter is held against the platform.
3. In a gun-carriage, a body adapted to rest upon a firing platform having a shouldered socket therein, a spindle having a shouldered head shaped and arranged to enter the socket and upon being turned to be locked against withdrawal from the socket, a positioning member rotatably mounted on said body and splined to said spindle, a clamping member carried by said positioning member and connected to said spindle, a driving member for operating said clamping member, and a ratchet mechanism connecting said driving member and said clamping member.
4. In a gun-carriage, a body adapted to rest upon a firing platform having a shouldered socket therein, a spindle having a shouldered head shaped and arranged to enter the socket and upon being turned to be locked against withdrawal from the socket, a clamping member connected to said spindle, said member being operable to draw said spindle toward said body to hold the latter against the platform, a positioning member for turning said spindle into and out of locking relation to the socket, said positioning member having a shoulder on which said clamping member is rotatably supported, said positioning member also being mounted to rotate upon said body and movable therein to retract said spindle to a position in which its head is above the platform, and a latch mounted upon the body for holding said positioning member and spindle in their retracted position.

CHARLES K. WOODMAN.
